UNITED STATES PATENT OFFICE.

ANTON TRUNK, OF BRIDGEPORT, CONNECTICUT.

DESIGN FOR A CORKSCREW.

SPECIFICATION forming part of Design No. 16,799, dated July 13, 1886.

Application filed April 15, 1886. Serial No. 199,036. Term of patent 7 years.

To all whom it may concern:

Be it known that I, ANTON TRUNK, a citizen of the United States, residing at Bridgeport, in the county of Fairfield and State of Connecticut, have invented and produced a new and original Design for a Handle for Corkscrews and Analogous Articles; and I do hereby declare the following to be a full, clear, and exact description of the invention, such as will enable others skilled in the art to which it appertains to make and use the same.

Reference is to be had to the accompanying drawings, in which Figure 1 is a view in side elevation of my newly-designed handle, and Fig. 2 a plan view of the same.

The leading feature of my design consists in the representation of a conventionalized figure of a female form distended across the shank of a corkscrew, so that when viewed in elevation said form will appear in a horizontal plane at right angles to the shank, the arms of the

figure represented as extended upwardly and crossing each other above the head, and the feet shown as interlocked.

A is the shank, and B the conventionalized figure.

I claim—

The design for a corkscrew herein described and shown, the same consisting of the corkscrew having the shank A and the handle B at right angles thereto, which latter consists of a conventionalized figure having the arms represented as extended upwardly and crossing each other above the head, and the feet shown as interlocked.

In testimony whereof I affix my signature in presence of two witnesses.

ANTON TRUNK.
